UNITED STATES PATENT OFFICE.

WILLIAM M. KELLY, OF WESTFIELD, NEW JERSEY.

PRINTING PRESS.

Original application filed August 6, 1921, Serial No. 490,290, and in Great Britain July 27, 1922. Divided and this application filed July 7, 1925. Serial No. 42,087.

The present invention relates to printing presses and more particularly to bed and cylinder presses of the two revolution type.

This application is a division of my application Serial No. 490,290, filed August 6, 1921, and relates to the operating and controlling means of the impression cylinder.

One of the objects of the invention is to provide an eccentrically operated impression means disposed at a considerable distance from the bearings of the cylinder so that the slight oscillation of the connecting rod will not have any substantial tilting effect on the bearings, and to dispose the means connecting the cylinder bearings and said eccentrics vertically and midway the length of said bearings so that no bending or tilting forces are transmitted to the cylinder. Because of this arrangement, it is possible to employ hollow cylinder housings bolted to the side frames of the base, if desired, as no tensional force or forces tending to separate the housings and frame are produced.

Another object is to provide an improved means for locking the manual throw-off against operation except when the cylinder is raised.

A still further object is to provide means for adjusting the position of the cylinder relative to the form so that after the press has been in operation the cylinder may be adjusted toward the form or bed to compensate for wear and use of the press.

Referring to the accompanying drawings for a detailed description of one embodiment of the invention:

Figure 1 is a partial sectional elevation of the press showing means for throwing on and off the impression;

Figure 2 is a vertical transverse sectional view through one of the side frames of the press and the associated cylinder housing; and

Figure 3 is a perspective view of the throw-off mechanism.

In the drawings, the cylinder is shown at 138 carried by bearings 139 guided by the hollow cylinder housings 140 secured to the side frame 35.

The means for throwing on and off the im-

pression includes a cam member 141 secured to shaft 44 of the bed and having a cam groove 142 receiving the cam roller 143 on the lever 144 pivoted on rod 145 carried by the frame. This lever at its free end has a pin 146 associated with a gab hook 147 which at its other end is pivotally connected to arm 148 on rock shaft 149. This rock shaft at its opposite ends has a pair of arms 150 and 151 connected by rods 152 to arms 153 on short shafts 154 each carried in bearings 155 by the side frames 35. Between the bearings 155 each of the shafts 154 has an eccentric 156 connected by an eccentric rod 157 to the cylinder bearing 139 directly above the same. It will be observed that the eccentric rods 157 are disposed within the cylinder housings 140 and are secured to the bearings 139 midway of their lengths. Furthermore the eccentrics are disposed vertically below the bearings 139 and at a considerable distance so that the slight pendulum motion of the eccentric rods has substantially no swinging effect on the bearings 139.

Rotation of the cam 141 effects oscillation of the eccentrics 156, thereby raising and lowering the cylinder. The position of the arms 150 and 151 when the impression is on is indicated by the dotted line 158 in Figure 1 and when off by the dotted line 159 in said figure.

Means are provided for adjusting the cylinder with respect to the form or bed so as to compensate for wear. In the present instance this is accomplished by varying the length of the rods 152, turnbuckles 160 being provided for this purpose.

In order to throw-off the impression actuating means, the gab hook 147 is disengaged from the pin 146. This should be done when the impression is off, and for the purpose of making the disengaging movement easy, there should be no force transmitted between the pin and the gab hook. For this purpose, the rock shaft 149 has an arm 161 (Figure 1) adapted to abut the stop 162 when the cylinder is in raised position, and this arm is held in engagement with the stop by the springs 163 acting on the arms 164 secured to the shafts 154. These springs

act between the arms 164 and fixed shoulders 165 carried by the side frames. The throw of the eccentrics is so small that the weight of the cylinders is not sufficient to tend to rotate the arms 153. The springs 163, however, tend to raise the cylinder, and therefore act to hold the arm 161 in engagement with the stop 162 and relieve the pin 146 and gab hook 147 so that the gab hook may be raised 10 without any frictional opposition.

It is desired to throw off the impression when a sheet is not properly fed on the feed board or not fed at all, and sometimes it is desirable to manually throw off the impression. For the purpose of manually throwing off the impression, a pedal 166 is provided on the side frame 35, being carried by a bracket 167 secured thereto. This pedal is secured to the lower end of a vertical rod 20 168, the upper end of which is swivelled to an arm 169. The spring 170 is interposed between the swivel and the bracket 167 and tends to hold the arm 169 in its upper position and thereby elevate the pedal 166. When the pedal is depressed, it may be turned slightly and locked under the lug 171 on the bracket 167. The arm 169 is loosely mounted on a rock shaft 172 and has an extension 173 on the opposite side of the shaft 30 adapted to strike a lug 174 on the arm 175 secured to the rock shaft 172. This latter arm is connected by a link 175' with the sheet controlled automatic means for throwing off the impression and the connection between the two arms is such that either the automatic means or the manual means can be operated independently. The rock shaft 172 adjacent the gab hook has a depending arm 176 carrying a pin 177 extending under the gab hook so that when the rock shaft is turned the gab hook will be elevated and carried out of engagement with the pin 146, thus rendering the cylinder raising and lowering means inoperative.

It is desirable that the impression actuating means be not disengaged when the impression is on, that is, when the parts are subjected to the stresses produced by forcing the cylinder against the form. In order to accomplish this in the present invention, means is provided to lock the cylinder throw-off against operation except when the cylinder is in elevated position and the impression off. As shown this is accomplished by providing a latch member 178 pivoted at 179 and having a shoulder 180 adapted to engage a hook 181 on the arm 176. The latch 178 is actuated so that it is carried out of engagement with the hook at the time 50 when the impression may be thrown off without bad results. At other times, the shoulder 180 engages the hook 181 and locks the rock shaft 172 against turning. For the purpose of controlling the latch 178, a link 182 is pivoted as at 183 to the latch and has a slot

184 therein receiving the pin 185 on the cam actuated lever 144. The length of this slot 184 is somewhat less than the throw of the pin 185, so that when the lever 144 is at the left of its throw (as viewed in Figures 1 and 3), the pin 185 moves the link 182 toward the left, thereby disengaging the latch from the hook 181 and permitting either manual or automatic throwing off of the impression.

Having thus described the invention, what is claimed as new and desired to be secured by Letters Patent is:

1. In a printing press, a base, a pair of hollow cylinder housings mounted at opposite sides of said base, a cylinder having bearings in said housings, a pair of eccentrics in the base, eccentric rods extending from said eccentrics through said housings and connected to said bearings and means to oscillate said eccentrics.

2. In a printing press, in combination, a base, a pair of hollow cylinder housings mounted on said base, a cylinder having bearings in said housings, means to raise and lower said bearings including vertical rods extending downwardly from said bearings through said housings to points within the base; and means carried by the base operative on the lower ends of said rods to reciprocate said rods.

3. In a printing press, in combination, a pair of side base members, a pair of hollow cylinder housings mounted on said members, a cylinder having bearings in said housings, eccentrics vertically below said bearings carried by said members, each eccentric having bearings on both sides thereof in its member, a vertical rod extending through a housing and connecting a bearing and eccentric and means to oscillate said eccentrics.

4. In a printing press, in combination, a cylinder, means to raise and lower said cylinder including eccentrics, arms secured to turn with the eccentrics, means to oscillate said arms, other arms secured to turn with said eccentrics and yielding means operative on the last mentioned arms tending to raise the cylinder.

5. In a printing press, in combination, a base, a pair of hollow cylinder housings mounted at opposite sides of said base, a cylinder having bearings in said housings, a pair of eccentrics in the base, eccentric rods extending through said housings and connected to said bearings, means to oscillate said eccentrics including rods, and means to adjust the length of the rods.

6. In a printing press, in combination, a base, a pair of hollow cylinder housings mounted at opposite sides of said base, a cylinder having bearings in said housings, devices mounted in said base for raising and lowering said cylinder, means extending through said housings for connecting said bearings to said devices, rods to actuate said

devices, and means to adjust the length of said rods.

7. In a printing press, in combination, a base, a pair of hollow cylinder housings mounted at opposite sides of said base, a cylinder having bearings in said housings, devices in the base for raising and lowering said cylinder, rods extending through said housings and connecting said bearings to said devices, rods to actuate said devices, and means to adjust the lengths of said rods.

8. In a printing press, in combination, a cylinder, means to raise and lower said cylinder, including a gab hook for actuating said means, a member connected to said hook adapted for connection with an automatic control mechanism, manual means to disconnect said hook, and means to render said manual means ineffective when the impression is on.

9. In a printing press, in combination, a cylinder, means to raise and lower said cylinder, including a gab hook for actuating said means, a member connected to said hook adapted for connection with an automatic control mechanism, manual means to disconnect said hook, and means to render said manual means ineffective when the impression is on including a latch.

10. In a printing press, in combination, a cylinder, means to raise and lower said cylinder, including a gab hook for actuating said means, a member connected to said hook adapted for connection with an automatic control mechanism, manual means to disconnect said hook, a latch to render said manual means ineffective when the impression is on, and means to trip said latch when the impression is off to permit actuation of said manual means.

11. In a printing press, in combination, a cylinder, means to raise and lower said cylinder including a cam, a lever oscillated by said cam and a gab hook associated with said lever; means to disconnect said hook, and means controlled by said lever to render said disconnecting means ineffective when the impression is on.

12. In a printing press, in combination, a cylinder, means to raise and lower said cylinder including a cam, a lever oscillated by said cam and a gab hook associated with said lever; means to disconnect said hook, and means controlled by said lever to render said disconnecting means ineffective when the impression is on including a latch member and a pin and slot connection between said lever and member.

13. In a printing press, in combination, a frame, bearing blocks slidably supported in said frame for vertical movements, a cylinder having trunnions mounted in said bearing blocks, eccentrics rotatable in said frame below said bearing blocks, rods connecting the eccentrics and bearing blocks, a rock

shaft journaled in said frame, connections between the rock shaft and eccentrics, an arm on the rock shaft, a gab hook pivoted to said arm, a lever fulcrumed to the frame engaged by said gab hook, means to oscillate said lever, and means to disengage said lever and gab hook only when the cylinder is in raised position.

14. In a printing press, in combination, a frame, bearing blocks slidably supported in said frame for vertical movements, a cylinder having trunnions mounted in said bearing blocks, eccentrics rotatable in said frame below said bearing blocks, rods connecting the eccentrics and bearing blocks, a rock shaft journaled in said frame, connections between the rock shaft and eccentrics, an arm on the rock shaft, a gab hook pivoted to said arm, a lever fulcrumed to the frame engaged by said gab hook, means to oscillate said lever, a second rock shaft having an arm with a pin thereon engaging under said gab hook, means to lock said second rock shaft at all times except when the cylinder is in raised position, a member connected to said second rock shaft adapted for connection with an automatic control mechanism, and manual means to rock said second rock shaft independently.

15. In a printing press, in combination, a frame, bearing blocks slidably supported in said frame, a cylinder having trunnions mounted in said bearing blocks, eccentrics rotatable in said frame below said bearing blocks, rods having straps at their lower ends surrounding said eccentrics and rigidly secured at their upper ends to said bearing blocks, means to oscillate said eccentrics periodically including a gab hook, means for disconnecting said gab hook, and means independent of the gab hook for preventing the operation of the disconnecting means during a predetermined portion of the period of oscillation of the eccentric.

16. In a printing press, in combination, a frame, bearing blocks slidably supported in said frame for vertical movements, a cylinder having trunnions mounted in said bearing blocks, eccentrics rotatable in said frame below said bearing blocks, rods connecting said eccentrics to said bearing blocks, arms rigid with said eccentrics, a rock shaft journaled in said frame, arms on said rock shaft, links connecting the arms rigid with the eccentrics to the arms on said rock shaft, another arm on said rock shaft, a gab hook pivoted to the last mentioned arm, a lever pivoted to said frame having a pin engaged by said gab hook and a cam oscillating said lever.

17. In a printing press, in combination, a frame, bearing blocks slidably supported in said frame for vertical movements, a cylinder having trunnions mounted in said bearing blocks, eccentrics rotatable in said

frame below said bearing blocks, rods connecting the eccentrics and bearing blocks, a rock shaft journaled in said frame, connections between said rock shaft and eccentrics, an arm on said rock shaft, a gab hook pivoted to said arm, a lever fulcrumed to the frame engaged by said gab hook, a cam os-
cillating said lever, and means to disengage said lever and gab hook only when the cylinder is in raised position.

10

In testimony whereof I hereunto affix my signature.

WILLIAM M. KELLY.
